FURRING STRIP BRACKET

Filed Aug. 8, 1928

UNITED STATES PATENT OFFICE

JOSEPH P. PAULISSEN, OF KANKAKEE, ILLINOIS

FURRING-STRIP BRACKET

Application filed August 8, 1928. Serial No. 298,272.

The invention relates to bonds for furring strips used in connection with walls and the like, and to which wall board, laths, or any other wall material may be attached, and has

5 for its object to provide a bond for the reception of a furring strip and comprising a looped portion through which the strip extends, and an arm adapted to be imbedded in the mortar between brick, tile, concrete blocks 10 or other wall elements for securely anchoring the bond and strip carried thereby to a wall.

A further object is to form the bond from a single piece of sheet material bent to form, and having an arm overlying the imbedded 15 arm and provided with a struck in lug having its outer side provided with a right angular shoulder engaging a similarly shaped shoulder in the anchored arm and cooperating therewith whereby outward movement of the 20 first mentioned arm is prevented, and allowing easy insertion of the furring strip.

A further object is to provide the arm of the bond with ridges whereby the arm would be positively held against outward movement when imbedded in the mortar. 25

A further object is to provide the bond loop with apertures through which securing means may be passed for anchoring the strip in relation to the bond. 30

35 A further object is to provide the bond with an angularly shaped loop for the reception of an angle iron, and the angle iron and loop with apertures through which securing wires may be passed for anchoring the angle iron against longitudinal movement. Also to provide the angle iron with apertures whereby a wall facing or other material may be attached to the wall.

40 A further object is to provide bond means whereby furring strips may be attached to a wall by imbedding arms of the bonds in the mortar between the wall elements, and to which furring strips a wall facing may be attached for forming an air chamber between the facing and the wall for ventilating and insulating purposes. 45

A further object is to provide separable interengaging means between the arms of the bonds whereby the loops may be slightly spread when inserting a furring strip. Also 50

to provide the loops with apertures through which securing means may be passed for anchoring the furring strips against longitudinal movement in the loops.

55 With the above and other objects in view the invention resides in the combination and arrangement of parts as hereinafter set forth, shown in the drawing, described and claimed, it being understood that changes in the precise embodiment of the invention may be 60 made within the scope of what is claimed without departing from the spirit of the invention.

In the drawing:—

65 Figure 1 is a perspective view of a portion of a brick wall showing the furring strips and wall facing applied thereto.

Figure 2 is a perspective view of one of the furring strip bonds.

70 Figure 3 is a vertical longitudinal sectional view through one of the bonds.

75 Figure 4 is a perspective view of a modified form of bond, showing the arm thereof crimped.

Figure 5 is a perspective view of a portion 75 of a tile wall showing the bond of a modified form carried thereby for supporting an angle iron.

80 Figure 6 is a vertical longitudinal sectional view through the loop end of the bond shown in Figure 5.

85 Figure 7 is a perspective view of the bond shown in Figure 5.

Figure 8 is a vertical transverse sectional view through a portion of the cement block wall, showing the bracket applied thereto.

90 Referring to the drawing, the numeral 1 designates a wall formed from courses of brick having mortar layers 2 therebetween. Although the wall is shown as formed from brick, it is to be understood it may be formed from stone, hollow tile, cement blocks or any other material, and applicant does not limit himself in this particular. Secured to one side of the wall 1 in spaced relation are horizontally disposed furring strips 3 formed from wood, and to which the wall facing 4 is adapted to be secured by nails 5.

95 The wall facing 4 may be of any material, for instance conventional form of wall board 100

formed from compressed pulp, laths or metal lathing, if it is desired to apply a plaster finish.

Imbedded in the layers of mortar 2 are the indented or crimped arms 6 of the furring bonds, the outer ends of which arms 6 terminate in downwardly extending strip receiving loops 7, the ends of which loops, indicated by the numerals 8, overlie the upper sides of the arms 6, and are anchored thereto by downwardly struck right angular shoulders 9 of the ends 8 and arms 6 as interlocking clearly shown in Figure 3 and which shoulders prevent outward movement of the ends 8 in relation to the arms 6 when said arms are imbedded in the mortar 2. The downwardly struck shoulders also stiffen the bond adjacent its outer end and obviate the necessity of using rivets which would weaken the bond arms, and at the same time allow the loop 7, as well as the loops 7a of the modified forms shown in Figures 5 to 8, to be easily spread for inserting the furring strips. By providing an indented or crimped arm 6, it will be noted that the arm, when imbedded, will be positively anchored in the mortar against longitudinal movement, however the arms 6 can be stamped to provide various kinds of anchoring shoulders, for instance letters as shown in Figure 2.

Referring to Figure 4, the structure is the same as shown in Figures 1 to 3 with the exception the arm 6 is provided with transverse crimps 10 for anchoring the arm in the mortar, crimps being shown instead of the stamped letters 11 shown on the arm 6 of Figure 2.

Referring to Figures 5 to 8 inclusive, in this form of invention the structure and operation is substantially the same with the exception the loops 7a are substantially triangular shaped in vertical and longitudinal section for the reception of angle bars 12, to which any kind of a facing may be attached, by attaching the same to the bars through spaced apertures 13 therein. The bars 12 are held against longitudinal movement within the loops 7a by means of wires 14, which are passed through the apertures 15 of the loops, and one of the apertures 13 of the bars, as clearly shown in Figure 6, after which the wire is twisted together at 16, therefore it will be seen that the bonds are held on the bars at fixed positions and during the building of the wall, either from brick as shown in Figure 1, or tile 17, shown in Figure 5, or cement blocks 18, shown in Figure 8, the arms 6 may be easily and quickly placed between the courses at predetermined positions, thereby attaching the furring strips to which wall facings may be attached for forming not only an anchoring means for the wall facing 4 as shown in Figure 1, but an

air space 19 behind the facing for ventilating purposes.

It will be noted that when it is desired to place the bonds on a furring strip, it will only be necessary to spread the arms 6 and 8, which will expand the loops of the bonds, and at which time the furring strips may be easily passed through the loops, and when in proper position the furring strips may be anchored to the bonds by wires 16 or by the nails 20 where a wooden furring strip is used as shown in Figures 1 and 3.

From the above it will be seen that a furring strip bond is provided which is simple in construction, formed from a single piece of metal, stamped and bent to form, the loops may be easily opened for inserting the furring strip, and when the loops are closed interengaging shoulders are provided between the arms 6 and 8 and means is provided for anchoring the strips to the loops.

The invention having been set forth what is claimed as new and useful is:

A furring strip anchor comprising a strip receiving loop, the ends of said loop terminating adjacent each other, arms carried by said loop ends, a plastic material in which said arms are embedded, said arms being in registration, struck in interengaging lugs, one within the other carried by said arms and cooperating with each other whereby lateral displacement of the arms in any direction in relation to each other is prevented, said plastic material forming means whereby said arms are maintained in engagement with each other, said lugs being spaced from the ends of the arms.

In testimony whereof I hereunto affix my signature.

JOSEPH P. PAULISSEN.
